INVENTOR.

Mary A. Murphy,

BY

Geo. P. Kimmel

ATTORNEY.

UNITED STATES PATENT OFFICE

MARY A. MURPHY, OF PITTSFIELD, MASSACHUSETTS

GARMENT SUSPENSION MEANS

Application filed December 12, 1929. Serial No. 413,615.

This invention relates to a suspension device for a pair of garments, and has for its object to provide, in a manner as hereinafter set forth, a device of such class designed primarily for use in connection with a pair of women's undergarments, one to be arranged within the other and including outer suspension elements for the outer garment of the pair, inner suspension elements for the inner garment of the pair, the inner suspension elements being supported by the outer suspension elements and in connection with the inner garment tending to prevent the slipping of the outer suspension elements for the outer garment from off the shoulders of the wearer, when the device is in garment suspension position.

A further object of the invention is to provide a garment suspension means including flexible elements which are adapted to be embodied as a permanent part of a two-piece combination undergarment, in which one piece of the two piece garment is in the form of a slip having shoulder straps, and in which the other piece of the two piece garment is in the nature of a vest adapted to be worn under the slip piece in snug engagement with the body of the wearer, with the flexible elements extending from the shoulder straps of the slip piece to the front and back of the vest piece, thereby providing a suspension for a combination undergarment.

A further object of the invention is to provide, in a manner as hereinafter set forth, for concealing an inner garment within a suspended outer garment and for suspending the inner garment from the suspension means for the outer garment and with the inner garment acting to maintain the suspension means for the outer garment on the shoulders of the wearer.

With the foregoing and other objects in view, the invention consists of the novel construction, combination and arrangement of parts as hereinafter more particularly described, and as illustrated in the accompanying drawings, wherein is shown an embodiment of the invention, but it is to be understood that the description and drawings are to be taken as illustrative and that the inven-

tion is intended to be limited in scope, only by the terms of the claim hereunto appended.

In the accompanying drawings, in which like numerals are employed to designate like parts throughout the same:—

Figure 1 is a front view of an embodiment of my invention showing the same in applied position.

Figure 2 is a perspective view of the slip with which my invention is associated.

Figure 3 is a back view of the embodiment shown in Figure 1.

Referring to the drawings in detail, the numeral 1 designates the body portion of a slip which is of usual construction provided adjacent its upper edge with a draw string 2 and further provided with a pair of shoulder straps 3, the respective ends of which are permanently secured to the inner face of the front and back of the body portion 1 in proximity to the top edge of the latter.

It is contemplated that the slip will be worn over a suitable garment, such as indicated at 4, which may be in the nature of a corset of modification thereof, or in the nature of a vest, and which fits snugly around the body of the wearer with the upper edge thereof resting under the armpits of the wearer.

My invention resides in the provision of means for anchoring the straps 3 to the garment 4 in such a manner that the shoulder straps not only will be prevented from slipping off the shoulders of the wearer, but further will be prevented from having any portion thereof dislodged with respect to the remaining portions thereof. In carrying out the aims of the invention, I secure to the under surfaces of the straps 3, substantially midway between the centers and forward ends thereof, a pair of flexible loops 5, which extend downwardly beneath the shoulder straps into looping engagement with a pair of buttons 6, arranged in spaced relation and secured to the outer face of the garment 4, at the front and adjacent the upper edge of the latter.

Each of the loops is formed from a flexible member bent upon itself and having its ends secured to the inner face of a strap. The loops are of a length to depend or

rather project below the top edge of the body portion 1 of the slip. The loops are arranged between the transverse medians of the shoulder straps and the ends of such straps.

5 Secured to the under surfaces of the straps 3, substantially midway between the centers and rearward ends thereof, is a pair of flexible loops 7, similar to the loops 5, which extend downwardly beneath the shoulder straps 10 into looping engagement with a pair of buttons 8, similar to the buttons 6, which are arranged in spaced relation and secured to the outer face of the garment 4, at the back and adjacent the upper edge thereof. The 15 buttons of each pair are spaced equal distances apart and the pairs of buttons are spaced an equal distance from the center line of the slip at the sides of the wearer whereby any dislodging movement of the straps 20 3 is opposed by snubbing actions of the flexible elements 5 and 7, such snubbing actions being applied equally to the straps 3 at equally spaced points on the latter and at points equally spaced from the body portion of the 25 slip. From the foregoing it readily will be seen that a slip having the suspension means applied thereto must necessarily hang evenly as any sidewise movement of either of the end portions of the shoulder straps, relative 30 to the other end portions thereof, is prevented. It is to be noted that, in the use of my invention, the flexible elements 5 and 7 are entirely concealed by the straps 3.

It is thought that the many advantages of 35 a garment suspension means in accordance with this invention will be readily apparent, and although the preferred embodiment of the invention is as illustrated and described, it is to be understood that changes in the 40 shape, size and arrangement of parts may be resorted to, so long as such changes fall within the scope of the invention as defined in the claim hereunto appended.

What I claim is:—

45 In combination, a slip for concealing a garment, a pair of spaced shoulder straps, each of said straps having its respective ends permanently connected to the inner face of the front and back of the slip in proximity to 50 the top edge of the latter, a pair of spaced flexible members supported by each shoulder strap, each of said members bent upon itself, having its ends secured to the inner face of a strap and providing a depending loop of a 55 length extending below the top edge of the slip for connection to the garment to suspend the latter in concealed position within said slip, said flexible members being concealed by 60 said shoulder straps.

65 In testimony whereof, I affix my signature hereto.

MARY A. MURPHY.
